UNITED STATES PATENT OFFICE.

THOMAS DEADERICK, OF NASHVILLE, TENNESSEE.

ADAPTER.

1,035,692.

Specification of Letters Patent. Patented Aug. 13, 1912.

Application filed October 16, 1911. Serial No. 655,056.

To all whom it may concern:

Be it known that I, THOMAS DEADERICK, a citizen of the United States, residing at Nashville, in the county of Davidson and State of Tennessee, have invented certain new and useful Improvements in Adapters, of which the following is a specification.

My invention relates to improvements in adapters and has for its object to provide 10 novel and simple means for converting an ordinary flush plug receptacle into a screw socket or a connection for a screw type attachment plug.

An object of the invention is to provide 15 an adapter for use in this connection which will prove exceedingly useful and desirable in houses, offices, public buildings, and the like, when it is desired to convert the ordinary flush plug receptacle into a connection 20 whereby the current may be conveyed to a lamp, motor, vacuum cleaner, flat-iron, percolator, or other electrical apparatus.

A further object of the invention is to provide 25 a device of the character stated which will be capable of instantaneous application and removal with reference to any type of receptacle, and to which the usual round screw attachment plug may be readily attached for connection with a lamp fixture 30 or the like.

Other objects of the invention are the provision of an adapter which will obviate the use of two or more different types of attachment plugs, as it is now required; which can 35 be made to accommodate one, two or three sockets, thus enabling one socket to be used for a connection with an incandescent lamp, another to be connected to the conducting wires of a motor, and so forth, as will be 40 readily understood. I may in this connection however, substitute for the sockets, binding posts or other electrical connecting devices, so that instead of screwing incandescent lamps or attachment plugs into the 45 sockets, it will be possible to connect wires to the binding posts direct, or I may use both socket and binding post, as the occasion requires.

My invention further consists of an 50 adapter embodying novel features of construction and combination of parts for service substantially as disclosed herein.

In the accompanying drawings, I have illustrated a practical physical embodiment of the best mode I have so far devised for ac-

complishing the objects heretofore stated, it being understood that such changes, alterations and modifications may be made as fall clearly within the scope of my invention without departing in any way from the 60 spirit thereof or sacrificing any of its advantages.

Figure 1 is a side elevation of the adapter, flush plug receptacle and incandescent lamp, showing the adapter in applied position. 65 Fig. 2 is a longitudinal sectional view of the adapter. Fig. 3 is an end view of the adapter as seen from the left in Fig. 2. Fig. 4 is an end view of the adapter as seen from the right in Fig. 2. Figs. 5 and 6 are perspective views of the adapter with two and 70 three sockets, respectively, for use when a cluster of lights is desired, binding posts being also shown for connection with conducting wires, as an alternative form of connection. 75

In the drawings:—the numeral 1 designates the flush plug receptacle generally, having the contact points 2, secured to the inner walls thereof, and the lead wires 3 80 connected to a suitable source of current.

The adapter proper comprises a block of wood, or other insulating material 5, of substantially circular shape and is cut away intermediate its length to form the rec- 85 tilinear-shaped portion 6. The upper or top portion of the block 5 is provided with a contact member or disk 7, which has a finger or strip 8 extending downwardly along the cut-away portion 6 of the block, and the 90 opposite side of the block is provided with the strip 9 having the spring-pressed clip or contact 10 formed integral therewith. Interposed between said contacts 7 and 10 is the disk of insulation material 11, the purpose of which is obvious. 95

The contacts 8 and 9 are secured upon the upper portion of the block 5 by any suitable means such as screws, or the like, while mounted upon the block 5 is the ordinary threaded socket 12 for attachment to the corresponding socket of an ordinary incandescent lamp. The current thus travels along contact 8 and is transferred to the screw shell 12 by means of the usual soldered connection 12^x, which solder also serves to retain the shell 12 upon the block 5. 100

The adapter is further provided with an outer casing or socket 13, of ordinary construction, said casing having the usual in- 110

sulation lining 14 and being provided with the opposite openings 15, the spring clips 16 and the adjusting screws 17, the purpose of which is apparent.

5 It will be readily seen from the above description, taken in connection with the drawings, that when the adapter is inserted into the flush plug receptacle and the contacts established, the current will follow the 10 contact strips 8 and 9. When the screw plug of an ordinary lamp and socket is screwed upon the threaded socket 12, the contact member carried by the lamp will bear upon the clip or contact 10 and the circuit 15 will thus be established.

In Figs. 5 and 6, respectively, sockets 18 are shown as entering the adapter at substantially right angles thereto, and the adapter is provided with the binding posts 20 or other electrical connections 19, to which conducting wires may be fastened, and this 25 form of adapter is particularly useful when a cluster of lights from a single receptacle is desired, it being understood that I do not limit myself to the precise details of construction herein specified. It will be also understood that there are a great many types of flush plug receptacles in common 30 use, in which the adapter must be fitted, and that for this reason I do not wish to confine myself to the precise form of block and spring contact fingers shown, but reserve the right to change the shape of the 35 fingers and block to conform with the different types of receptacles, provided that I do not depart from the essence and spirit of the invention, which is to provide means for converting an ordinary flush plug receptacle

into a connection for a screw type attachment plug.

I claim:—

1. The combination with a lamp and a flush plug receptacle having contact points, of an adapter comprising a block, spring contact plates attached thereto, conductor 45 disks formed integral with said plates, an insulation disk interposed between said disks, and a threaded socket for attachment with said lamp.

2. A device of the character described, 50 comprising a block having a rectilinear cut-away portion, spring contact plates attached thereto, conductor disks formed integral with said plates and secured upon the top of said block, an insulation disk interposed 55 between said conductor disks, a threaded socket, an outer casing, an insulating material therebetween, and means for securing said casing upon said block.

3. The combination with a flush plug receptacle, having contact points, of an adapter fitting in said receptacle and contacting with said points, said adapter comprising a block, spring contact plates attached thereto, conductor disks formed integral with said plates, an insulation disk interposed 65 between said disks, and means for conveying the current from said conductor disks to a plurality of electrical connections.

In testimony whereof I affix my signature in presence of two witnesses.

THOMAS DEADERICK.
